WEFT REPLENISHING LOOM

Walter H. Wakefield, Worcester, Mass., assignor
to Crompton & Knowles Loom Works, Worcester, Mass., a corporation of Massachusetts

Application June 3, 1944, Serial No. 538,569

12 Claims. (Cl. 139—230)

This invention relates to improvements in multi-stack weft-replenishing looms and it is the general object of the invention to provide means for moving the stack selector out of register with the bobbin releasers of the stacks for the purpose of preventing an untimely indication of weft exhaustion from causing a weft replenishing operation of the loom.

In filling mixing pick and pick weft-replenishing looms it is customary to employ under the bobbin magazine two shifting shuttle boxes which shift in a four-pick cycle such that the upper box moves to inactive position on the first pick of a four-pick cycle and returns to action on the third pick. When the weft detector is in front of the lay at the magazine end, as in the present instance, it rises and falls in register with the top shuttle box to detect the condition of weft therein. If the detector should indicate exhaustion during the first pick of the cycle as the boxes are rising such indication can properly be communicated to the magazine for replenishment of the weft supply in the upper box, since the latter will be in high position immediately under the magazine. If, however, the detector should indicate weft exhaustion during the third pick while the boxes are moving down, such indication should not be communicated to the magazine because the shuttle box will then be too low to receive a bobbin from the magazine.

Multi-stack bobbin magazines have a selector which registers one at a time with a series of bobbin releasers, one for each bobbin stack, and when the detector indicates a weft exhaustion it causes the selector to rock and operate the releaser with which it registers, thereby initiating a replenishing operation and setting the magazine for operation. It is an important object of my present invention to hold the selector out of register with respect to all of the releasers during the third pick of the cycle so that should the detector give indication of weft exhaustion as the shuttle boxes are descending no bobbin releaser will be operated and a replenishing operation will not be initiated.

In the particular type of loom previously mentioned it is desirable to draw bobbins in rotation from the several bobbin stacks so that the full capacity of the magazine can be utilized. A recently developed mechanism effects this result by the use of a stepped stop having a different position and step for each releaser. When the stop tends to move toward the selector it cannot ordinarily do so because the selector is in an interfering position. It is another object of my

present invention to provide means not only to move the selector to the aforesaid non-registering position, but at the same time move it to a non-interfering position with respect to the selector stop.

In addition to the shuttle boxes already mentioned, filling mixing pick and pick weft-replenishing looms have shuttle boxes at the end thereof opposite the magazine. The boxes at the magazine end shift on the first and third picks of the four-pick cycle, while the boxes at the opposite end shift on the second and fourth picks. It is a further object of my invention to move the selector to the aforesaid non-registering position by means operatively connected to the boxes at the end of the loom opposite to the magazine.

The aforesaid stop has two general movements, one caused by gravity toward the selector and the other caused positively in a direction away from the selector. The operating mechanism for the stop is such that when moving away from the selector the stop may move far enough to take the correct step thereof out of stopping position, and time must be allowed for it to recover from any excess movement so that the correct step can move to stopping position before the selector is returned for registry with one or another of the releasers. It is another object of my invention to hold the selector in its non-interfering position a considerable length of time during which the stop can assume its correct position, and this result is accomplished by connecting the selector to the shuttle boxes at the end of the loom opposite the magazine. These boxes hold the selector in a non-interfering position for the greater part of two picks of the loom.

With these and other objects in view which will appear as the description proceeds, my invention resides in the combination and arrangement of parts hereinafter described and set forth.

In the accompanying drawings, wherein a convenient embodiment of my invention is set forth,

Fig. 1 is a front elevation of a weft replenishing loom having my invention applied thereto,

Fig. 2 is an enlarged detailed front elevation of the structure shown at the right end of Fig. 1,

Fig. 3 is a side elevation looking in the direction of arrow 3, Fig. 2, showing the magazine as seen from the center of the loom,

Fig. 4 is an enlarged vertical section on line 4—4 of Fig. 3, parts being omitted,

Fig. 5 is a reduced horizontal section on line 5—5, Fig. 4, showing the selector in non-inter-

fering and non-registering position in dotted lines,

Fig. 6 is a perspective view of the four-step stop for the stack selector used with my invention,

Figs. 7 to 10 are diagrammatic views showing the various positions of the stop and the control lever therefor, and

Fig. 11 is a detail plan view of the weft detector locking in the direction of arrow 11, Fig. 3.

Referring particularly to Fig. 1 which shows a front view of a pick and pick weft replenishing filling mixing loom having shuttle boxes on each end thereof, the loom frame 15 supports a lay 16 which reciprocates backwardly and forwardly in usual manner and is provided at its right end with a gang GR of two shifting shuttle boxes and at its left end with a similar gang GL. The gang GR has top and bottom shuttle boxes 17 and 18, respectively, mounted on a box lifter rod 19 which is raised and permitted to fall by a chain 21 forming part of a box shifting mechanism and connected to and leading upwardly from a collar 22 secured to the lifter rod 19. Chain 21 is trained over a sheave 23 on the lay and then extends across the loom and is trained around another lay carried sheave 24 from which it extends downwardly around a sheave 25 and then upwardly over sheave 26. From sheave 26 the chain 21 extends around a sprocket 27 rotatable about a fixed axis and is connected to a lever 28 operated by a connector 29 of the box shifting mechanism K forming part of the well-known Knowles head.

The shuttle box gang GL has top and bottom shuttle boxes 30 and 31, respectively, mounted on a box lifter rod 32 connected to a box chain 33 trained over sheaves 34 on the lay and extending thence substantially parallel to chain 21 and trained around a second sprocket 35 similar to and coaxial with and in front of sprocket 27. Chain 33 then connects with a lever 36 similar to and in front of lever 28 and operated by a second connector 37 in front of connector 29 and included in the box shifting mechanism K. The latter is of usual construction and it is thought sufficient to state that a pull on either box chain 21 or 33 will lift the corresponding box gang, while slackness in either chain permits the associated gang to fall.

The gangs GR and GL shift in well-known manner to place three shuttles in active position for so-called pick and pick filling mixing operation. These shuttles are indicated in dotted lines in Fig. 1 at S', S2 and S3 in boxes 17, 18 and 31, respectively, and the picking mechanism at the right and left ends of the loom designated generally at P and P', respectively, operate alternately to pick the shuttles in such order that they follow each other at one-pick intervals, each shuttle after being active for one pick being shifted to inactive position, while another shuttle is being shifted into active position for the next pick. It is not thought necessary to set forth the details of the shiftings of the two gangs GR and GL during successive picks of the loom operation, since they are well understood and may be similar to the sequence shown for instance in my prior Patent No. 2,065,776.

Each gang of boxes operates on a four-pick cycle, being in down position for two successive picks to place its upper shuttle box in active position and then being up for the next two successive picks to place the bottom shuttle box in active position. The shiftings of the gangs GR and GL are out of phase with each other by one

pick so that one or the other of the gangs shifts every pick of the loom when the lay is in the forward part of its reciprocating movement, but the two gangs do not shift simultaneously. Thus, when gang GR shifts upwardly on one pick gang GL will be stationary with respect to the lay. On the next pick gang GL will shift upwardly and gang GR will be at rest in high position relatively to the lay. On the third pick gang GR shifts downwardly while the gang GL remains in high position, and on the fourth pick gang GL shifts down while gang GR remains in low position. In the description which follows particular reference will be made to the four-pick cycle of shifting operations for the gang GR and it will be assumed that the cycle starts when shuttle box 17 is down and in active position but is about to rise to inactive position as the lay moves forwardly.

The magazine for supplying reserve bobbins is designated generally at M and is provided with four bobbin stacks which, starting at the front of the loom and reading backwardly, are indicated at I, II, III and IV, see Fig. 3. These stacks are preferably all supplied with bobbins of the same kind, and each stack has associated therewith a bobbin releaser, these releasers being indicated more particularly in Fig. 3 at 40, 41, 42 and 43. Each releaser has upper and lower operating lugs 44 and 45, respectively, and is guided in well-known manner for vertical reciprocation on the inner bobbin butt guiding plate 46 of the magazine M. The bottom of each of the bobbin releasers is associated with a bobbin delivering cradle of well-known construction, a part of which is indicated in Fig. 3 at 47. The releasers are normally down and their associated cradles are empty, but when any releaser is raised its cradle rocks to receive a bobbin from the corresponding stack and a dog 48 pivoted on the upper end of the releaser is moved by its spring 49 over a bar or shelf 50 secured to a shaft 51, see dotted lines Fig. 4. When a raised releaser is lowered to normal position the associated cradle rocks to empty itself of the bobbin which it previously received and at the same time dog 48 rocks shaft 51 clockwise, Fig. 4, to lower a rod 52, Fig. 3, for the purpose of raising latch 53 on transerrer arm 54 to transfer position, after which the released bobbin in transfer position indicated in dotted lines at B, Fig. 3, is inserted into the shuttle in box 17.

A releaser selector and operator or actuator 55, shown more particularly in Figs. 3 and 5, comprises a rod 56 horizontally slidable in front and back bearings 57 and 58, respectively, formed as integral parts of the inner magazine frame 46. This rod has secured thereto a casting 59 having front and back lifting and depressing fingers 60 and 61, respectively. Casting 59 has a web 62 for cooperation with a rocking lever 63 pivoted on rod 56, see Fig. 5, and connected to a depending rod 64 shown in Figs. 2 and 3. The selector can rock to raise and lower its fingers 60 and 61 and can also shift laterally to change registry of the fingers with respect to the operating lugs 44 and 45 of the several releasers.

Lateral shifting of the selector is accomplished by mechanism shown more particularly in Figs. 3 and 5 and including a grooved collar 65 secured to the rear end of rod 56 and receiving a lug 66 on the upper end of a lever 67 pivoted as at 68 with respect to the magazine frame. A tension spring 69 tends normally to move lever 67 for

wardly to the position shown in Fig. 3 to register finger 60 with releaser 40.

Rocking movement of selector 55 to operate the releasers is controlled in part by a weft detector D, see Figs. 1, 2 and 3, made somewhat similar to the detector shown in Payne Patent No. 2,050,066. The weft detector is mounted for vertical movement under the magazine so that it may remain constantly in register with the top shuttle box 17. The detector includes a base or plate 70, see Fig. 11, horizontally slidable on a support 71 guided for vertical reciprocation on a bracket 72, see Fig. 2, held in fixed position on a large stud 73 forming part of the magazine. The lower end of the support 71 is connected to a rod 74 the lower end of which is attached to the box lifter rod 19 at 75, see Fig. 1. As the box lifter rod rises it acts through rod 74 to lift the support 71 and carry the detector upwardly in register with the box 17 as the latter rises from active position aligned with the lay to inactive position above the level of the lay. When box 17 descends the detector moves down, and the latter is thus kept in horizontal alignment with box 17 at all times.

The detector D is of the side slipping type and has a feeler finger 76, see Fig. 11, pivoted on base 70 at 77, and a spring 78 between a lug 79 on the support 71 and the base normally urges the latter rearwardly. When the finger engages an ample supply of weft W in shuttle box 17 it is moved forwardly to slide the base 70 frontwardly on support 71. If the finger 76 engages an empty bobbin it slides laterally in usual manner and spring 78 holds the base in rear position, a condition which results in an indication of weft exhaustion.

The base 70 has secured to the forward end thereof a depending arm 82 which coacts with a lever 83 secured to and projecting upwardly from a short shaft 84 mounted for rotation on the bracket 72, see Figs. 2 and 11. A second lever 85 also secured to shaft 84 and rocking with lever 83 has its upper end connected to a rearwardly extending controller pin 86 the position of which determines whether or not the loom is to have a replenishing operation.

A vertically reciprocating block 90 is guided on bracket 72 and has pivoted thereto an actuator lever 91 the left end of which as viewed in Fig. 2 is connected to the lower end of the previously described rod 64. The right end of lever 91 extends through a guide slot 92 in a horn 93 fixed with respect to the bracket 72 and across which the controller pin 86 normally extends, being held in such position by torsion spring 94 acting in usual manner on shaft 84, see Figs. 2, 3 and 11.

The block 90 and lever 91 are operated by a rod 95, see Fig. 2, and are very similar to corresponding parts in the usual multicolor weft replenishing loom, and start to move down when the lay is in front center position on the first and third picks of the aforesaid four-pick cycle.

When the detector finger 76 engages a bobbin with ample weft W in box 17 as the latter rises it is pushed forwardly and causes arm 82 to move levers 83 and 85 forwardly to pull controller pin 86 forwardly from slot 92 and lever 91. The right end of lever 91, Fig. 2, thereupon has an idle down motion and rod 64 remains at rest, causing no rocking of lever 63 or the selector 55. If, on the other hand, the detector should encounter an empty supply of weft in box 17, it remains in rear position and arm 82 will not rock shaft 84, hence the controller pin will remain in

rear position across slot 92. Under these conditions pin 86 interrupts down motion of the right end of lever 91, Fig. 2, and becomes a temporary pivot around which the lever rocks, causing rod 64 to descend and rock lever 63 and selector 55 in a counter-clockwise direction as viewed in Fig. 4. The fingers 60 and 61 thereupon rise from the full line to the dotted line position of Fig. 4 and raise to the dotted line position shown in Fig. 4 whichever bobbin releaser is registered with the selector. Lever 91 acts to raise fingers 60 and 61 only when the detector indicates weft exhaustion on either the first or the third pick of the aforesaid four-pick cycle.

Immediately following each downward movement of block 90 the latter has an upward movement to cause lever 91 to engage and rock around a fixed stop 96, see Fig. 2, thereupon lifting rod 64 and causing fingers 60 and 61 to be lowered to the dot and dash line position of Fig. 4 for the purpose of lowering any previously raised releaser. This last operation occurs on alternate picks and during the latter part of the first and third picks of the aforesaid cycle and independently of whether or not the detector has indicated weft exhaustion. During the second and fourth picks of the cycle the block 90 is stationary and is incapable of transmitting an indication of weft exhaustion by the detector to the selector 55. The selector can therefore be rocked only during the first and third picks of the aforesaid cycle and not during the second and fourth picks when gang GL is shifting. This is an important relationship, as will be apparent in the description to follow, and differs from the usual weft replenishing multicolor loom.

A rod 97, see Figs. 2, 3 and 4, is raised and lowered by rocking of shaft 51 and controls the usual thread cutter and resetting mechanism designated generally at 98, see particularly Fig. 3.

The greater part of the matter thus far described may be made as heretofore, much of it being as set forth more particularly in Ryon Patent No. 1,030,748 and Turner copending application Serial No. 403,326, now Patent No. 2,360,529.

The gang GR shifts on a four-pick cycle, but lever 91 operates on a two-pick cycle, and it is for this reason that the detector can give indication of exhaustion twice for each complete shifting of the gang GR. The first of these indications can occur on the first of the four picks of the cycle and may properly be followed by a rocking of the selector 55 to initiate replenishment, but the second indication occurs when gang GR is descending at an improper time to initiate replenishment because of the fact that box 17 would be too low to receive a bobbin from the transfer position B.

Part of my invention relates to means for preventing an indication of weft exhaustion which may occur on the third pick from causing upward movement of any releaser to initiate an operation of the magazine. In carrying this feature of my invention into effect I permit all of the connections between the detector and the selector to remain unchanged, but shift the selector out of register with all the releasers during the third pick of the cycle. To accomplish this result I connect lever 67 to some part which shifts in timed relation with the gang GL, as shown in Fig. 1.

A connector 100 attached as at 101 to lever 67, see Fig. 3, extends rearwardly and is led around a guide sheave 102 on the loom frame

and then upwardly over a second guide sheave 103 on the loom arch 104. The connector 100 then extends across the loom and is connected to a member or lever 105 pivoted at 106 to the arch. The lower end of lever 105 is connected by rod 107 to chain 33 at 108. Thus it is that when gang GL rises due to a pull on chain 33, rod 107 moves to the right, Fig. 1, thereby rocking lever 105 counter-clockwise to pull connector 100 and rock lever 67 rearwardly, or to the left, Fig. 3, thereupon moving the selector 55 to the dotted line position of Fig. 5 where the fingers 60 and 61 are out of register with all the releasers. This occurs during the second pick of the aforesaid cycle when the block 90 is stationary and the fingers 60 and 61 are in neutral position shown in full lines, Fig. 4. During rearward movement of selector 55, therefore, there is no danger of collision between the fingers 60 and 61, and lugs 44 and 45.

Gang GL and the mechanism associated with it for controlling lever 67 remains in its shifted position to maintain the selector in non-registering position with respect to all of the releasers during the third pick and until the gang GL again shifts downwardly during the fourth pick. Thus it is that selector 55 is in an inoperative position during the third pick of the four-pick cycle and if the weft detector should indicate exhaustion during this pick the selector can rock in the usual manner but it will not lift any of the releasers and therefore will not initiate a replenishing operation of the loom.

When gang GL shifts down rod 107 moves to the left, Fig. 1, and rocks lever 105 clockwise, thereby slackening connector 100, and spring 69 moves the selector forwardly. This occurs during the fourth pick when the block 90 is stationary, and the selector is thus returned to a position where it can register with and operate one or another of the releasers during the first pick of the next four-pick cycle.

The position of the gang GL is such during the first pick of the four-pick cycle that it does not interfere with movement of lever 67 and the latter can respond to positioning mechanism to be described and operative to cause registry of the selector with the four releasers in rotation.

In looms of the type to which my invention more particularly relates the weft of all the reserve bobbins in the four stacks of the magazine is wound with the same kind of filling. In order to take advantage of the full capacity of the magazine it is desirable to distribute the selection of bobbins with respect to the stacks during successive replenishing operations of the loom. This result I accomplish by stop mechanism for the selector similar to that set forth in copending application Serial No. 520,264, now Patent No. 2,364,979, but unlike that application, the stop mechanism shown herein is permitted to move to certain of its positions by a control exercised by means under control of the gang GL.

Referring particularly to Fig. 3 I have shown a small stand 120 secured to the magazine end plate 46 and having a lever 121 pivoted thereto between its ends as at 122. The forward end of lever 121 is provided with a pin 123 extending through a slot 124 in the upper end of a depending lifter rod 125. The rod 125 has secured to the lower end thereof a stop 126 having four steps 127, 128, 129 and 130 corresponding, respectively, to releasers 40, 41, 42 and 43, see Fig. 6, and areas a, b, c and d, respectively, on the upper edge of lever 121. This stop is made in

the form of an inverted U and straddles the rod 56 of the selector and by its position determines with which of the releasers the selector 55 shall register.

The vertical positions of the stop 126 is determined by the several angular positions of lever 121 and these positions in turn result from operation of the several releasers. To effect angular movement of lever 121 each of the releasers has the dog 48 thereof provided with an integral upwardly extending hook 135, see Fig. 4, shown more particularly in co-pending application Serial No. 515,203, filed by Patterson, now Patent No. 2,363,620. The four operating areas a, b, c and d of lever 121 are each positioned for operation with the hooks 135.

With the parts in the position shown in Fig. 3 rod 125 is in high position and the low stop 127 is in the path of the selector 55 so that finger 60 is held in register with the front releaser 40 by spring 69. When releaser 40 has a reciprocating movement incident to a replenishing operation involving stack I its hook 135 engages area a and rocks lever 121 in a clockwise direction as viewed in Fig. 3 and from the full line to the dotted line position of Fig. 7 to place area b in position for cooperation with the hook of releaser 41 and also lower pin 123 sufficiently to permit rod 125 and stop 126 to fall when they are free to do so for the purpose of placing step 128 in the path of the selector to register the latter with releaser 41.

The stop, however, will not be able to move downwardly far enough to place step 128 in controlling position due to the fact that the selector is in an interfering position, being in register with releaser 40. It is necessary therefore to move the selector 55 rearwardly to permit the stop 126 to fall, and this result is accomplished by the same mechanism which moves the selector rearwardly to a non-registering position with respect to all of the releasers.

The transfer incident to reciprocation of releaser 40 is completed during the first pick of the four-pick cycle and the gang GL shifts during the second pick and moves the selector rearwardly to a non-interfering position, whereupon stop 126 is able to fall and place step 128 in the path of the selector. After the selector reaches the dotted line position shown in Fig. 5 it remains there during the third pick of the four-pick sequence and even if the weft detector should give another indication of weft exhaustion, releaser 41 will not be operated and the sequence of bobbin deliveries from the stacks will not be interrupted by a second delivery while the same shuttle is in box 17. This relationship grows out of the fact that the gang GL shifts only every second pick of the loom, and after shifting on the second pick remains in its new position through the third pick and until bottom center position of the lay in the fourth pick.

When gang GL shifts down during the fourth pick of the cycle spring 69 tries to move the selector 55 to its extreme forward position, but the selector will be stopped by step 128 with finger 60 in register with the second releaser 41. The selector is therefore back in position to initiate a second replenishing operation of the loom on the first pick of the next or any ensuing four-pick cycle if the detector should indicate weft exhaustion.

The second replenishing operation will involve upward movement of selector 41 and when the latter is depressed to release a bobbin from the

second stack II the corresponding hook 135 will engage surface *b* which is nearer the pivot of lever 121 than area *a* and rock the lever so that rod 125 and stop 126 will try to fall to their lowest position. During this operation hook 135 of releaser 41 engages area *b* and moves lever 121 from the full line to the dotted line position of Fig. 8, thereby placing surface *d* in its highest position where it is located for engagement with the hook of releaser 43. Step 130 now tries to fall into the path of the selector but cannot do so until the selector is again moved rearwardly as already described. When the selector again moves forwardly it is stopped by step 130 with finger 61 in register with releaser 43 and area *d* is in active position.

When the third transfer is to occur involving a bobbin from the rearmost stack IV the hook of releaser 43 will engage area *d* and rock lever 121 in a counter-clockwise direction from the full line to the dotted line position of Fig. 9 to lift the stop 126 so that surface 129 thereof will be in the path of the selector. This is a positive control exercised by the lever not requiring rearward shift of the selector, but this shifting is provided for nevertheless in order to avoid complications which might otherwise be necessary if rearward shifting were to be avoided on those transferring beats when the stop 126 is moved upwardly. When selector 55 again moves forward from its rearmost position it is registered with releaser 42 by step 129.

The fourth transfer involving a bobbin from stack III will result in a second counter-clockwise movement of lever 121 by engagement of surface *c* with the hook of releaser 42 the effect of which is to move lever 121 from the full line to the dotted line position of Fig. 10 and return lever 121 to its starting position with the pin 123 up so that the stop 126 again has its low surface 127 in the path of the selector.

It is necessary to provide for downward movement of stud 123 when the selector is in an interfering position with respect to the stop 126, and it is for this reason that slot 124 is provided in the upper end of connector 125. The presence of this slot, however, makes it possible for the stop 126 to have an excess upward movement when stud 123 is raised. Thus, when the hook 135 of the rearmost releaser 43 rocks the lever 121 in a counter-clockwise direction as viewed in Fig. 3 the pin 123 will be given a quick upward movement and the stop 126 will rise high enough to move stop surface 129 above the path of the selector 55. This excess upward movement is only temporary and the stop almost immediately recovers itself by gravity. Immediately following this excess upward movement, however, the selector is moved to the rear dotted line position of Fig. 5, as already described and is held there for the greater part of two picks, thereby giving the stop 126 ample time to recover its excess upward movement and allow it to fall to its proper position with stop surface 129 in the path of the selector. This same operation involving an excess upward movement of the stop also occurs when lever 121 is being rocked back to its starting position shown in full lines in Fig. 3.

From the foregoing it will be seen that I prevent the detector from initiating replenishment on a wrong pick of the loom and also permit the stop 126 to fall to stopping position in the path of the selector by the simple expedient of moving the selector away from the stop to a non-registering position with respect to all of the releasers.

These two results are accomplished by connecting the selector to the shifting shuttle boxes at the end of the loom opposite the magazine. It will further be seen that the bobbin releasing mechanism controlled by the detector D and including the selector 55 constitute one instrumentality which should be inoperative during the third pick of the cycle, and that the lever 121 and associated parts constitute a second instrumentality which should operate to deliver bobbins from the stacks in rotation without possibility of an interruption by a wrong transfer on said third pick, and that both of these instrumentalities are caused to operate properly by moving the selector to a non-registering and non-interfering position relatively to the releasers and stop 126, respectively. In the second of these instrumentalities the lever 121 which is moved by the releaser hooks serves as a control means for the stop 126 and allows the latter to fall into the path of the selector when in certain of its positions.

Having thus described my invention it will be seen that changes and modifications may be made therein by those skilled in the art without departing from the spirit and scope of the invention and I do not wish to be limited to the details herein disclosed, but what I claim is:

1. In a weft replenishing loom having at the replenishing end thereof a weft supply in a shifting shuttle box which is in raised inactive position on the first and second picks of the loom and is in down active position on the third and fourth picks of the loom, the loom having a plurality of bobbin releasers and a selector registerable with the releasers one at a time and having an operating movement upon indication of weft exhaustion to actuate the releaser registered therewith, said selector being capable of moving to a non-registering position with respect to all of said releasers, a weft detector to detect said weft supply and capable of indicating weft exhaustion on the first and third picks of the loom, means controlled by the detector and operative on the first and third picks of the loom when the detector indicates weft exhaustion to give the selector said operating movement, said means being idle during the second and fourth picks of the loom, and means operative during the second pick of the loom to move the selector to said non-registering position out of register with respect to all of the bobbin releasers and maintain the selector in said non-registering position during the third pick of the loom.

2. In a weft replenishing loom having at the replenishing end thereof a weft supply in a shifting shuttle box which is in raised inactive position on the first and second picks of the loom and is in down active position on the third and fourth picks of the loom, the loom having a plurality of bobbin releasers and a selector registerable with the releasers one at a time and having an operating movement upon indication of weft exhaustion to actuate the releaser registered therewith, said selector being capable of moving to a non-registering position with respect to all of said releasers, a weft detector to detect said weft supply and capable of giving indication of weft exhaustion on the first and third picks of the loom, shuttle boxes at the end of the loom opposite said shifting shuttle box having a shifting movement on the second pick of the loom, and means moving in timed relation with said shuttle boxes to move the selector to said non-registering position with respect to all of the releasers during the sec-

ond pick and maintain said selector in said non-registering position during the third pick.

3. In a weft replenishing loom having at the replenishing end thereof a weft supply in a shifting shuttle box which is in raised inactive position on the first and second picks of the loom and is in down active position on the third and fourth picks of the loom, the loom having a plurality of bobbin releasers and a selector registerable with the releasers one at a time and having an operating movement upon indication of weft exhaustion to actuate the releaser registered therewith, said selector being capable of moving to a non-registering position with respect to all of said releasers, a weft detector to detect said weft supply and capable of indicating weft exhaustion on the first and third picks of the loom, shuttle boxes at the end of the loom opposite said shifting shuttle box which are in one position during the first pick of the loom and shift to be in a different position during the third pick of the loom, and means operatively connected to the boxes and effective when the latter shift to said different position to move the selector to said non-registering position with respect to all of the releasers.

4. In a weft replenishing loom having at the replenishing end thereof a weft supply in a shifting shuttle box which is in raised inactive position on the first and second picks of the loom and is in down active position on the third and fourth picks of the loom, the loom having a plurality of bobbin releasers and a selector registerable with the releasers one at a time and having an operating movement upon indication of weft exhaustion to actuate the releaser registered therewith, said selector being capable of moving to a non-registering position with respect to all of said releasers, a weft detector to detect said weft supply and capable of indicating weft exhaustion on the first and third picks of the loom, a member occupying one position during the first pick of the loom and moving to occupy a different position during the third pick of the loom, and connections between the member and the selector to move the latter to said non-registering position with respect to all of the bobbin releasers when said member moves to said different position.

5. In a pick and pick filling mixing weft replenishing loom having a magazine provided with a plurality of bobbin releasers and a selector registerable with the releasers one at a time, said loom having shuttle boxes at the magazine end of the loom which operate in a four pick cycle and shift during the first and third picks of the cycle, the loom having other shuttle boxes at the opposite end of the loom which shift during the second and fourth picks of the cycle, the selector operative upon indication of weft exhaustion to actuate the bobbin releaser registered therewith, a weft detector capable of indicating weft exhaustion in one of the first named shuttle boxes during the first and third picks of the cycle, and means moving in timed relation with said other shuttle boxes and effective to maintain the selector in a non-registering position with respect to all of the bobbin releasers during the third pick of the cycle.

6. In a pick and pick filling mixing weft replenishing loom having a magazine provided with a plurality of bobbin releasers and a selector registerable with the releasers one at a time, said loom having shuttle boxes at the magazine end of the loom which operate in a four pick cycle and shift during the first and third picks of the cycle, the loom having other shuttle boxes at the op-

posite end of the loom which shift during the second and fourth picks of the cycle, the selector operative upon indication of weft exhaustion to actuate the bobbin releaser registered therewith, a weft detector capable of indicating weft exhaustion in the upper one of the boxes at the magazine end of the loom during the first and third picks of the cycle, means operatively connected to said other shuttle boxes and said selector to move the latter to a non-registering position with respect to all of the bobbin releasers when said other shuttle boxes shift on the second pick of the cycle and maintain said selector in said non-registering position during the third pick of the cycle.

7. In a pick and pick filling mixing weft replenishing loom having a magazine provided with a plurality of bobbin releasers and a selector registerable with the releasers one at a time and operative upon indication of weft exhaustion to actuate the releaser registered therewith, said selector being movable to a non-registering position with respect to all of said releasers, shuttle boxes under the magazine which shift alternately toward and away from the magazine, a weft detector capable of indicating weft exhaustion in one of said shuttle boxes when the latter are shifting either toward or away from the magazine, and means effective when said shuttle boxes are shifting away from the magazine to maintain the selector in a non-registering position with respect to all of said releasers.

8. In a pick and pick filling mixing weft replenishing loom having a magazine provided with a plurality of bobbin releasers and a selector registerable with the releasers one at a time and operative upon indication of weft exhaustion to actuate the releaser registered therewith, shuttle boxes under the magazine which operate in a four cycle and shift toward the magazine on the first pick of the cycle and shift away from the magazine on the third pick of the cycle, a weft detector capable of indicating weft exhaustion when said shuttle boxes are shifting either toward or away from the magazine, means moving during the second pick of the cycle from one position to another position thereof and remaining in said other position during the third pick of the cycle, and connections between said means and the selector operative when said means moves to said other position thereof to effect movement of the selector to a non-registering position with respect to all of the bobbin releasers.

9. In a weft replenishing loom having at the replenishing end thereof shifting shuttle boxes which are up for two successive picks and then down for two successive picks, the loom having a bobbin releaser and a selector tending to move in a given direction along a path and registering with the releaser, said selector having an operating movement to actuate the releaser upon indication of weft exhaustion, a weft detector capable of indicating weft exhaustion when the shuttle boxes are up and also when they are down, a stop movable into the path of the selector, control means for the stop moved from one position to another position by the releaser when the latter is operated by the selector, said stop when the control means is in said other position thereof tending to move into the path of the selector but prevented from doing so due to the fact that the selector is in an interfering position, and means moving the selector out of registering position with respect to the releaser to prevent the selector from operating the releaser when

said shuttle boxes are down, and also move said selector in a direction opposite to said given direction to a non-interfering position to permit the stop to move into the path of the selector.

10. In a weft replenishing loom having a set of bobbin releasers and a selector registerable with the releasers one at a time and tending to move in a given direction relatively to the releasers, said selector having an operating movement upon indication of weft exhaustion to actuate the releaser registered therewith, shifting shuttle boxes operating on a four pick cycle and moving a weft supply to inactive position on the first pick of the cycle and moving the weft supply to active position on the third pick of the cycle, a weft detector having detecting operations with respect to the weft supply during said first and third picks and capable of indicating weft exhaustion during both of said detecting operations thereof, a stop for the selector tending to move from one position thereof to a different position thereof in the path of the selector consequent upon actuation of a releaser registered with said selector to change registry of the selector relatively to the releasers but prevented from moving to said different position thereof due to the fact that the selector is in an interfering position, and means effective between said detecting operation of the detector on said first and third picks to move the selector out of registry with all of the releasers and also move the selector in a direction opposite to said given direction to a non-interfering position with respect to said stop to permit the latter to move to said different position thereof in the path of the selector.

11. In a weft replenishing loom having a plurality of bobbin releasers and a selector registerable with said releasers one at a time and having an operating movement upon indication of weft exhaustion to actuate the releaser registered therewith, shifting shuttle boxes operating on a four pick cycle and moving a weft supply to inactive position on the first pick of the cycle and moving the weft supply to active position on the third pick of the cycle, a weft detector having detecting operations relatively to the weft supply during said first and third picks and capable of indicating weft exhaustion incident to each of said detecting operations, a stop for the selector tending to move from one position thereof to a different position thereof in the path of the selector to change the registry of the selector relatively to the releasers but prevented from moving to said different position thereof due to presence of the selector in an interfering position, means operated by the releaser registering with the selector when the latter has an operating movement and operatively connected to the stop to hold the latter in said one position thereof prior to said operating movement of the selector

and permitting the stop to move to said different position of the latter subsequent to said operating movement of the selector, and means to maintain the selector in a position of non-registry with respect to all of the releasers when the detector has the detecting operations thereof on said third pick to prevent actuation of any releaser by said selector, said means also moving the selector to a non-interfering position relatively to said stop, whereupon the latter moves to said different position thereof, and means cooperating with the stop when the latter is in said different position thereof to register the selector with a different releaser.

15. 12. In a weft replenishing pick and pick filling mixing loom having a plurality of stacks of reserve bobbins and having a gang of shifting shuttle boxes at each end thereof, the gang at the replenishing end shifting upwardly toward said stacks to place the top shuttle box thereof in transfer position on the first pick of a cycle of four successive picks and shifting down on the third pick of the cycle to move said top shuttle box to non-transferring position, two instrumentalities, one to release a bobbin for a replenishing operation and the other to determine the order in which bobbins are to be released with reference to their stacks of origin for successive replenishing operations, the first instrumentality including a weft detector always in register with said top shuttle box of the gang, a bobbin releaser for each stack operative when reciprocated to release a bobbin for transfer from the associated stack, a selector registerable with the releasers one at a time and having movements on either the first or the third pick of said cycle to effect reciprocation of any releaser registered therewith, provided the detector indicates weft exhaustion on said first or third picks, the second instrumentality including a stepped stop for the selector movable to as many different positions relatively to the selector as there are stacks of bobbins, each position corresponding to registry of the selector with a different releaser, 40 means tending during a succession of replenishing operations to effect a succession of movements of said stop to the different positions thereof but prevented from doing so due to presence of the selector in an interfering position relatively to 45 the stop, and means operative to move said selector out of register with all of said releasers to prevent reciprocation of any releaser during said third pick of the cycle and also move the selector to a non-interfering position relatively to 50 said stop, to the end that no releaser may be reciprocated during said third pick or the selector permitted to remain in an interfering position to interrupt the order in which bobbins are released.
